FORM FOR BUILDING CONSTRUCTION

Oscar M. Stanley, New York, N. Y.

Application March 16, 1931, Serial No. 523,001

11 Claims. (Cl. 25—131.5)

This invention relates to apparatus adapted for use in the erection of concrete construction. More particularly, the invention relates to forms and means for supporting forms in which concrete is moulded.

Prior to my invention, concrete buildings almost universally have been made by the erection of temporary wooden forms. The construction, fitting and erection of these forms has involved the expenditure of large amounts for skilled labor and for lumber which, after use on one or a few of such forms, has been destroyed so far as its usefulness is concerned. The cost of such form work is one of the most important items in the cost of concrete construction. It is usual, in erecting such forms, to support the framing from the permanent steel frame by wiring to the steel beams of the permanent frame of the building cross timbers beneath the soffits of the beam forms. Upon these cross timbers, the beam forms and panel centering forms have been supported by additional framing and by fitted wooden facings.

It has also been suggested to use forms of sheet metal or other materials more permanent than wood, and which are intended to be reused many times. Such forms, however, ordinarily require fitted frames erected in the same manner as for wooden forms, and furthermore are practical only where the sizes of beams and arches are exactly the same throughout a large building or in many buildings which are to be erected close together. Where, as is more often the case, the sizes vary, the cost of supplying and handling the variety of permanent forms frequently exceeds the cost of building and fitting the temporary wooden forms. Obviously, where an odd size is required, it is impracticable to use permanent forms in any case, so that at best they can only partially replace the handmade wooden forms built and fitted on the job.

Accordingly, it is an object of my invention to provide a form system of which the permanent members are so designed and arranged that they may be used in standard sizes, regardless of the dimensions of the form in which they are used, while those parts which must be fitted are made of materials which are inexpensive in themselves, and which may be cut and/or shaped with little labor and expense.

Another object of my invention is to provide form members which can be assembled and removed from the finished concrete with a minimum of labor and the parts of which are either so cheap that their destruction after each use is

relatively unimportant or are adapted to be reused indefinitely with little or no cost for reconditioning.

With these and other objects in view, I have developed a system of form work in which the weight of the mass of concrete is carried on a frame made up of standard sized members, so designed and arranged that they may be assembled with very little labor and in substantially any size, as required for each particular job. I have found that by divorcing the frame of the mould from its covering, i. e., the facing or lining of the mould, that it is possible to make the form entirely flexible, that is, adaptable to substantially any size required of it, while the form covering may be made of an inexpensive sheet material which may be readily cut and/or shaped, and which may be left in place after the concrete has set, or may be removed and destroyed, or if conditions of labor justify, may be salvaged and reused.

In the accompanying drawings, I have shown several embodiments of my invention which are illustrative of the ways in which my invention may be applied to practical construction problems.

Fig. 1 is a cross-section through a concrete form showing the relation of the various frame members to the mould facings, the permanent frame and the concrete itself.

Fig. 2 is a cross-section through the form frame taken on line 2—2, Fig. 1.

Fig. 3 is a detail showing one form of supporting member.

Fig. 4 is a top plan view illustrating the arrangement of frame members.

Fig. 5 is a section taken on line 5—5 of Fig. 4.

Fig. 6 is an elevation of the bracket shown in Fig. 5 with its end partially broken away.

Fig. 7 is a cross-section similar to Fig. 1, illustrating another embodiment of the invention.

Fig. 8 is a cross-section on line 8—8 of Fig. 7.

Fig. 9 is a fragmentary top plan view of the embodiment shown in Figs. 7 and 8.

Figs. 10 and 11 are views similar to Figs. 5 and 6, showing parts which may be used in place of those illustrated in Figs. 5 and 6.

Figs. 12 and 13 show in section and elevation, respectively, a fastening means which may be used in place of that illustrated in Fig. 3.

Fig. 14 illustrates another fastening device which may be used in place of those shown in Figs. 3 and 12.

Fig. 15 illustrates another means for supporting the form frame from the permanent frame.

Fig. 16 is a cross-section similar to Fig. 1, but showing another type of form frame particularly

adapted for use at the ends of panels and around the juncture of beams of different dimensions.

Fig. 17 is a cross-section taken on line 17—17 of Fig. 16.

5 Fig. 18 is a detail view of a crossbar used in the embodiment of the invention illustrated in Fig. 17.

Fig. 19 shows another method of supporting the form frame upon the permanent frame of a building.

10 In Figs. 1 to 6, inclusive, I have illustrated an embodiment of my invention which includes certain features of special advantage for many purposes. In this embodiment, angle brackets 40 are hung from the permanent beams 41 by the 15 stirrups of saddle bars 42. These angle brackets, in the present instance, include a vertical member 43, one horizontal member 44, and a second horizontal member 45 at right angles to the first. The member 44 is braced to the member 43 by 20 the strut 46, and the horizontal members 44 and 45 are preferably braced together, e. g., by gusset plates 47.

Outwardly extending flanges 48 and 49 on the members 43 and 44, respectively, are transversely slotted for the reception of the strip members 50 of steel or other suitable material. The spacing of these slots will depend upon the type of material which is to be used for the mould facing or lining 51, and should be such that, with the lining 30 in place as shown, it will be capable of supporting the weight of concrete thereon between alternate strips 50, that is to say, with strips in only half of the slots. The slots in the members 43 are advantageously sloped slightly inward, enough to 35 prevent the strips 50 from slipping out when jarred or because of vibration; this has also the advantage that the horizontal thrust of the concrete is opposed by the weight of the strips 50 between the members 43.

40 The strips 50 may for example be flat as shown or T, L, U or O section, preferably being held spaced and positioned with their strongest dimension toward the form. These strips may also be laid upon a flat surface of the principal frame members 44 without the use of slots, especially if the T, U or O forms are chosen.

In erecting the form, the brackets 40 are hung over the beams 41, preferably in pairs. This may be accomplished by bolting two such brackets 50 together by means of the saddle bar 42, or other equivalent connecting means, and lowering them together over the beam; or the saddle bar may first be put in place over the beam and the brackets lifted into place either singly or after being joined by means of the crossbar 52.

If the brackets have been hung before their ends are joined by the crossbar 52, the latter is now put into place and secured to the members 43 at a level adapted to serve as a principal support 60 for the bottom of the beam, and so as to hold the members 43 spaced apart as required for the beam form.

In Fig. 1, I have shown, as an adjustable means of securing crossbar 52 to the members 43, blocks 65 53 having crossed openings adapted respectively to receive the crossbar 52 and the vertical members 43. As shown in Fig. 1, each of the latter are drilled at suitable intervals and the blocks 53 are correspondingly drilled, so that holes in the three 70 members may be aligned for the reception of the pin 54. Obviously, instead of the holding blocks 53, other means for securing the cross member to the vertical members may be used. For example, they may be simply bolted together; or a wedge 75 or clamp may be used in holding the block, in

place of the pin and holes; or the opening for the crossbar may itself be made wedge-shaped, so that the weight of the concrete on the crossbar 52 and/or the horizontal thrust of the member 43 will serve to clamp the two against one another. 5

Other similar brackets 40 will be placed along the beam 41 at intervals depending upon the width of the span and the weight of the floor which is to be poured. Similar brackets will also be hung from the corresponding beam 41 at the 10 opposite side of the opening. If the opening is less than twice the length of the brackets 40, opposite brackets may be arranged in staggered formation from opposite sides, so that their ends will overlap and preferably will be positioned so that 15 along their overlapped parts the slots for the strips 50 will be in approximate alignment. If the width of the opening is only slightly greater than twice the length of the brackets, they may be placed in any desired arrangement, whether 20 staggered or aligned. If, however, the opening is substantially greater in width than twice the length of the brackets, it is desirable to bridge the gap between their ends by means of a supplementary member 55, which, in the present instance, is shown as a channel having a series of spaced holes in its end, so that it may be bolted at opposite ends to the ends of the brackets 40 to 25 bridge any length between them within a substantial range. The ends of opposite brackets 30 may be joined also, so as to reduce any tendency to sag. The tops of these bridging members 55 are made with slotted flanges like the flanges 49 on the brackets 40.

If the distance between the ends of the brackets 35 40 is greater than can be safely supported upon the brackets themselves, an additional supporting member 56 may be used under the middle of the supplementary members 55. This cross beam 56 may be supported from the permanent frame, for 40 example, as shown in Figs. 7 and 9, or as in Figs. 15 and 16, with the difference, however, that it would be supported at a lower level than shown in these figures, in order to permit it to pass beneath the supplementary frame members 55. 45

At the ends of the opening, brackets 58, such as those shown in Figs. 5 and 6, or in Figs. 10 and 11, are hung from the end beam 57 of the permanent frame, e. g., in substantially the same manner that the brackets 40 are hung from the beam 41. The vertical members 43a of the brackets 58 may be substantially the same as the corresponding members 43 of the brackets 40. Similarly, the horizontal members 45a may be similar to the corresponding members 45 of the brackets 55 40. In this case, however, the short receptacles 59 or 59a replace the horizontally extending supporting arms 44, and in these receptacles a number of strips 60 similar to the strips 50 are held, overlapped to any extent required to fit them 60 to the width of the opening. These strips 60 support the ends of the strips 50 between the brackets 58.

Figs. 10 and 11 illustrate brackets which may be used in place of the brackets shown in Figs. 65 5 and 6. In this case, instead of receptacles 59, upstanding flanges 59a are provided, and these flanges are closely slotted to permit a plurality of strips 60 to be positioned side by side.

Another method of supporting the ends of the 70 strips 50, which is possessed of considerable advantage, is illustrated in Figs. 16 to 18. In this method, the strip 120 is bolted to a hanger 42 positioned over the end beams of a panel. This strip 120 has a horizontal shelf 121 and a vertical 75

- slotted flange 122, into the slots of which the strips 50 are fitted. The back of the member 120 rises vertically to the corner 123, and is not slotted. Thus it serves to support the edges of the form covering 51 at the corner, and also serves to position the ends of the strips 50. With this type of end member, the strips may be inserted into their slots in the flange 122 and pushed in until they abut the back of the member 120. Thus no care is required to bring their ends exactly or approximately to a corner, as is the case with the embodiments shown in Figs. 4, 5, 10 and 11. If desired, these end members 120 may be made integral with, or may be bolted to vertical members 15 similar to the members 43 or 43a, shown in Figs. 1 to 11, inclusive, and the beam forms assembled in the same manner as already described.

Adjustment of the length of the strips 120 may be effected by securing two of such members together with e. g., a Z-section 124, which fits over and is bolted to the ends of the strips 120.

In Figs. 16 to 18, I have also illustrated the case in which a larger beam joins a smaller beam. In this case, vertical members 43c are advantageously secured to the ends of the end members 120, and in the same plane, so that their edges face the beam which is at right angles to these end members. As shown in Fig. 16, the bottoms of these vertical members 43c may be joined and the form around the beam 41 may be built up in the same manner as already described above. In this case, however, the ends of the form for the beam 57 are also supported upon a cross member between the members 43c. Thus, as shown in Fig. 17, cross members 52a are positioned beneath the beam 57 on the vertical members 43c at right angles to the cross members 52. These cross members 52a may be identical with the cross members 52, merely using adjusting blocks similar to the blocks 53 of Fig. 1, but adapted to receive the member 52a at right angles to the vertical member 43c. A simpler form is shown in Fig. 18, in which the cross member 52a is formed of a rod 127, bent near the middle so as to form slots for the strips 50, and a second rod 128 welded thereto for support. These rods are spaced so that their ends may be received in the holes of the vertical members 43c and may extend therebeyond as far as is necessary, depending upon the width of the form about the beam 57.

With any of the above, the principal frame members in place, as described, the strips 60 and 50 are positioned in the receptacles and slots provided for them, and are overlapped as shown in Fig. 4 to any extent required. Similar strips 53 are placed in the sides and bottoms of the beam forms as shown in Fig. 1; and the framework is ready for the reception of the form covering 51.

The material which I have found to be most 60 advantageous for the mould covering is a heavy fiber board or corrugated paper board, the surface and edges of which are made entirely waterproof, most advantageously a fiber board thoroughly impregnated throughout with a hard asphalt. A waterproofing material should be chosen which will not substantially decrease the rigidity or strength of the paper and advantageously may be one which, when set or dried, will serve to stiffen the paper. Thus, a heavy bituminous 65 material, tar or resin is advantageous, or the paper may be stiffened in other ways sufficiently so that a soft waterproofing material, e. g., a non-drying oil, may be used. When the paper board thus used is waterproofed only at the surface, it is important to thoroughly waterproof the

edges, and preferably to close the joints between the edges of adjacent sheets, in order that the water may not penetrate into the sheet from the edges and thereby cause any lessening of strength or rigidity of the paper. This may be accomplished, for example, by painting with solution or emulsion of asphalt or other waterproofing material. Paper board may be supplied at such low cost that its destruction after a single use makes it a relatively unimportant item of expense. It may, however, remain in place and serve a permanent function, e. g., as waterproofing, sound or heat insulation, or as a plaster base. Where the paper is to be removed, it is preferably such as has a smooth, hard surface, but where it is to remain in place, it may well have a more open surface with which the concrete may form a better bond. Thus, a common type of insulating board made of coarse bagasse fiber, when thoroughly impregnated and strengthened with a waterproof binder such as hard asphalt, serves very well in such cases.

The paper is readily cut to the sizes required, and when necessary may be bent or folded on the job, or even moulded to fancy shapes. In some cases, however, it is better to avoid folding of the sheet, and in these cases, I prefer to use angle irons in all concave corners of the mould. Such angles are shown, for example, at 61 in the corners of the beam form frame, and at 62 in the corners of the columns.

I have found numerous materials other than paper board to possess advantage for use in lining or facing moulds. Thus, a metal lath, particularly one of the expanded metal type, may be used, especially where the concrete to be poured is of a relatively stiff or coarse mix which will not tend to drain through the opening of the lath. Where a lath of the "high rib" type is used, the ribs may, to some extent, replace parts of the assembled framing, and in such cases fewer of the strips 50 need to be used, or the brackets 40 may, if necessary, be positioned closer together, and the strips 50 entirely omitted. The use of metal lath has the advantage that if it is left in place it will form an excellent plaster key, so that the work of lathing over the concrete will be entirely eliminated.

Similarly, in place of paper board, steel sheets may be used. Over the relatively wide openings, this can be effected with considerable economy, since such sheets may be overlapped as much as is necessary to make them cover the opening without extending beyond its boundaries. Such ridges as are formed in the concrete by the edges of these overlapping form plates may not be objectionable, when the surface is to be plastered. The use of metal for the beam forms, however, is less advantageous, since in these forms it is not ordinarily practicable to permit overlapping; and the differences of size may, therefore, require the sheet metal to be scrapped after each use. Even cutting sheet metal to size and scrapping it after each use in this manner permits of substantial economy over the present methods of building wooden forms to order. The use of paper, however, is possessed of such greater economy that it will not ordinarily be desirable to resort to the use of sheet metal.

In some cases, particularly where the corrugated paper type of mould plates are to be joined edge to edge, it is desirable to support the free edges of the mould plates, and this may readily be accomplished by the use of a metallic strip having a low vertical flange to extend between

- the mould plates, and wider horizontal flanges to extend under them and support their edges. Such a supporting member may have prongs extending horizontally from the vertical flange 5 which enter into the paper sheets and hold them more closely positioned on these supporting irons. The edges of the mould coverings may also be held by strips 125 above them which become embedded in the concrete and which serve to 10 anchor wires 126 passing between the edges of the coverings and around some of the strips 50 to support them during removal of the forms as hereinafter described. I have shown only two of the wires 126, but it is understood that more 15 will be used as required to hold the strips 50 when the forms are dismantled.

In Fig. 5, the saddles 42 are shown with horizontal ends threaded for the reception of nipple nuts 63. These horizontal ends are made of a 20 length such that they will come approximately to the surface of the concrete, but will not extend substantially therebeyond. The nuts 63 extend through suitable holes in the horizontal members 45a and when screwed over the ends of 25 the saddles, serve to hold the brackets in place. Another similar type of saddle is shown in Fig. 3, in which the ends extend down from the flange of the beam at an angle toward the corner of the horizontal member 45. Nipple nuts 63 in this 30 case extend diagonally through the horizontal member 45 to engage the saddle bolt 42. This latter type of saddle is less desirable because of difficulty of accurately aligning the nut with the bolt. Another type is shown in Fig. 10. I have 35 found that the most satisfactory means for supporting the form frame is a saddle threaded for reception of a bolt, as shown in Fig. 1.

Instead of using saddles which are to remain in the concrete, as in Figs. 1 to 11, chairs 64 may 40 be provided to hold the heads of the bolts 42a above or near the level of the finished floor. The bolts may be protected from the concrete by tubes 65 of waterproofed paper, sheet metal, or other water-resisting material, or by grease, paraffin, 45 etc., applied directly to the bolt. After the concrete has set, the nuts may be removed from such bolts, and the bolts driven back through the floor to be reused.

In Fig. 19, I have shown another type of saddle 50 which may be removed after the concrete has set. In this case, the saddle is a U-member 43d supported upon the yoke 129, which in turn rests upon the block 64a. This block may be made in 55 tapered form, so that it may be removed from the concrete after the forms have been removed. The ends or stirrups of this U-shaped saddle may be protected from the concrete in any way, e. g., as described above in connection with the bolts 42a.

In Figs. 12 to 14, I have shown other ways of 60 securing the supporting members to the form frame members. In Figs. 12 and 13, the saddle is made in the form of a strip or bar bent to the desired form. A slot 66 near the end of this bar is covered on the back by a waterproof pan 67. A fastener 68 is mounted in the horizontal member 45 of the bracket so that it may be inserted 65 into the slot 66. By turning this fastener at right angles to the slot, it serves to hold the member 45 to the saddle member 42b. The pan 67 prevents the concrete from setting around the end of the fastener 68, and thereby permits the fastener to be turned back to its horizontal position for removal after the concrete is set.

In Fig. 14, the strap or bar 42c is made with 70

vertical slots 66a, into which hooks 68a on the horizontal member 45 of the bracket 40 are inserted. The slot 66a in this case is made higher at one side than at the other, and the hook 68a is made with an overhanging portion adapted to enter the wider part of the slot, but to be engaged in the narrower part of the slot when it is moved horizontally with the horizontal member 45.

Figs. 7, 8 and 9 illustrate a form frame which 10 may be used in place of, and is in many ways superior to, the frame shown in Figs. 1, 2 and 4. In this illustration, the brackets, which may be hung from the beam in any of the ways described above, are made with U-shaped receptacles 69, 15 to which the vertical members 43a are secured. A horizontal member 45 similar to the corresponding member of Figs. 1, 2 and 4 is secured over the beam by means of saddle bolts or other support. The U-shaped receptacle 69 is made with 20 slots along its top for reception of the strips 50. In this receptacle may be positioned a frame member 71 which may be similarly provided with slots for the strips 50, and which is of a width to bring its upper surface substantially flush 25 with the top of the U-shaped receptacle.

In use, the brackets are assembled about the beam in the same manner as the brackets of Figs. 1, 2 and 4, and the beam forms are held thereon in substantially the same way. However, 30 instead of the horizontal arms 44 of the brackets 40, the frame members 71 serve to carry the weight of the frame and the concrete between the brackets. These frame members 71 may be of metal, e. g., channel steel or I-section steel, 35 cut to suitable length or made adjustable, e. g., by drilling and bolting in suitable relation, as shown in Fig. 1 for the members 55 and 44. Or, instead of steel, wooden timbers may be used. These may be made similarly adjustable, e. g., 40 by overlapping and bolting together or strapping together slidably, or they may be cut to length for the wider openings, and gradually cut down for the narrower openings, as they become damaged and worn in service. It will be no 45 noticed, however, in the embodiment shown in Fig. 7, that the U-shaped receptacle 69 is made of substantial length. By this means, a substantial variation in width of openings may be taken care of, using the same length of supporting member 50 71. Frequently this will accommodate all variations of width occurring in a large building. The strips 50 and the mould coverings 51 may be assembled on the supporting members 71 in substantially the same way as on the members 44 and 55 55. A tension member 145 may be used to brace this construction.

I have also shown in Fig. 7 the use of bolts having extensions 146 for securing the horizontal members 45 to the saddles 42. The extensions 60 146 are screwed up against the flange of the beam 41 and serve to hold the vertical members 43a accurately spaced on either side of the beam, and to prevent rocking of the saddle 42 on the beam. Similar bolts may advantageously be 65 used near the bottom of the beam screwed into a slide 147 on the vertical member 43.

Similar brackets to those just described may also be used in connection with any of the brackets 40 and 58, if the receptacles 69 are positioned 70 at a lower level. In this case, they may be used to support the member 56 for very wide arches which cannot be satisfactorily supported upon the unaided brackets 40 or beams 71.

After the concrete has set in any of the above 75

forms, the forms themselves may be readily removed and quickly transported to another location for re-use in the erection of additional concrete. In the removal of these forms, the principal frame members are first loosened. If the secondary frame members are held, e. g., by means of wires 126, the principal frame members may be removed entirely, leaving the secondary frame members held to the concrete by said wires. 5

10 Or, in some cases, the entire form frame may be removed at once, lowering it, e. g., by means of mechanical lifting equipment, or even allowing it to drop. I have found it preferable, however, either to use wires, such as the wires 126, and to 15 remove the secondary frame members, a few at a time, after removal of the principal frame members, or, if wires are not thus used, to first loosen the principal frame members without removing them, and then to remove the secondary frame 20 members from between the principal members and the concrete before completely removing the principal members.

From the above, it will be understood that I have provided a novel type of form construction 25 using frame members of standard size assembled in such manner that a form lining or facing of substantially any dimensions may be supported thereon. The form linings and facings are made of material so light as to be readily cut and/or bent to size and shape, and readily positioned on the frame, and so inexpensive as to be left in place or scrapped after a single use. Such form facings and linings may also serve a function 30 subsequent to the moulding operation, as in the case where a metal lath is used to provide a plaster key, or a waterproof fibre board is used for waterproofing, soundproofing or heat insulation.

The reduction of initial cost is perhaps the 40 feature of greatest importance, but it is not by any means the only important advantage gained by my invention.

The finish with which the job can be left when the forms are removed is in many cases no less 45 important than reduced cost. Where a smooth surfaced waterproof paper board is used and particularly where the joints are waterproofed, the surface of the concrete may be left so smooth that a plaster coat will be unnecessary. Even 50 where fancy mouldings are required, they be made by securing special fancy moulds, e. g., of moulded and waterproofed paper pulp, or plaster, onto the mould facing. Thus, panels, mouldings, and many other types of surface ornamentation 55 may be made integral on the concrete and with no need for a separate plastering or other finishing operation.

I have found that it is particularly advantageous to use a waterproofed paper board, by 60 which I mean, of course, to include fibre board, since it can be easily moulded in relatively inexpensive dies, and after the concrete has set, it can be readily removed, even where it has been formed with undercut portions. The use of such forms 65 makes possible a much wider choice of architectural effects, since the designs used in plaques, mouldings, cornices, etc., may be of substantially any design, without the necessity for avoiding undercut portions. I have found that the forms used for this purpose are most advantageously 70 made of a paper board impregnated with asphalt, wax, or other thermoplastic waterproof binder, since such board may be easily moulded when hot, and yet will be possessed of substantial rigidity when cold. Where intricate designs are to 75

be moulded into the concrete which are not standard, but which are designed specially for the location, these may be moulded in clay or plaster, etc., and the paper may be moulded over such model by heating and pressing it against the 5 model by fluid pressure, or by pressure exerted through some plastic or other fluent material, such as a fine granular or powdered material. The fluid used as the pressure medium may be hot water, for example, or it may advantageously 10 be a hot bath of the impregnating binder, such as asphalt, paraffin, etc. The pressure thus exerted forces the paper against the model, so that it will conform to the model, even in minute detail, and regardless of undercut parts. If any 15 parts are undercut to a large extent, it may be necessary to disintegrate the model in order to avoid injuring the paper form when it is removed. It is an advantage, however, of the use of paper of this kind that after it is cooled it is possessed of 20 considerable elasticity, and it may therefore be removed from models having only slight undercuts without injuring the paper mould.

Another feature of great importance is the 25 lessened confusion attendant upon erection and dismantling of forms. There is no rough carpentering necessary and hence no space need be set aside for sawing, fitting and storing of lumber; and other operations may be carried on which heretofore have had to give way to the rough 30 carpenter. In the present instance all parts except the linings are brought to the job ready to put in place and they can be erected as soon as they are available. All parts, when the forms are 35 dismantled, can be in lengths short enough so that they may be loaded on trucks and carried by the mechanical hoist to the floor where they are to be next used, with saving of the manual labor now explained in passing planks and timbers one by one from floor to floor.

When the forms are removed, the frame members are at once ready to carry to the next floor with no delay for breaking apart the forms, nor for separating the good lumber from the broken 45 pieces or other salvaging operations. Instead, the forms are unbolted and taken down, their members piled on the trucks or other conveying means, and when the frames are all taken away, the linings may, if desired, be removed and carried 50 away for baling, or for any other use to which they are to be put. All may be complete in a fraction of the time required to take off and dispose of the old wooden forms. The floor may then be turned over to the next trade to do its 55 work, without interference.

Although I have described my invention above and illustrated it in the drawings as applied to buildings in which concrete is cast onto a permanent steel frame, it will be apparent that 60 many features of my invention are not limited to such use, but may be applied as well to the erection of structures of concrete reinforced with bars, or mesh, or even of unreinforced concrete, 65 and the forms may be supported by guy ropes, wires, rods, etc., or a temporary rigid frame may be set up externally of the moulds to hold them during the moulding operation.

It is to be understood that many of the features shown and/or described in connection with each modification and particular embodiment of my invention are independent of the particular embodiment or modification in which they are shown and the various corresponding features 70 75

shown in the various figures of the drawings may, to a large extent, be used interchangeably.

Ordinarily each type of unit which must be moulded in erection of a building has a fairly uniform width throughout, but may vary widely in length. Thus, the vertical members 43 and cross bars 52 of the beam mould frames, the cross members, 44 and 55 or 71, are required to accommodate relatively little variation as compared with the average dimensions for which they are used. In length, however, the variation is wide and this is accommodated by the parallel overlapping members, which may be used in any number of lengths and overlapped to any extent required. Thus, in the most advantageous embodiment of my invention, this relative uniformity of one dimension is taken advantage of. The principal frame members are placed on the dimension of greatest uniformity and are repeated as required along the other dimension, while the secondary frame members are laid across the primary members in as many lengths and with as much overlap as the dimension of each form requires.

I have referred to the supports from the beams as "saddles", and to their parts which extend down to engage the form frames as "stirrups". It will be understood, of course, that each saddle may have one or more stirrups.

The word "overlapping" I have used broadly to include any arrangement in which at least one part extends substantially beside or beyond another adjacent part which it is said to overlap.

I claim:

1. In a form for moulding concrete into buildings, having a pre-formed permanent frame, a support comprising a saddle member adapted to engage the top of a member of said permanent frame and having stirrups extending diagonally downward and outward from the top of said frame member, a cantilever having a horizontal member extending beneath the form to afford it support, and a vertical member rigidly connected to said horizontal member, connected to one of said stirrups and extending down beside the permanent frame member, and a spacer against which said vertical member bears below its point of connection to the stirrup, said spacer forming a fulcrum for said cantilever, so that the force on said stirrup is made diagonal with a horizontal component outward from the permanent frame member, as well as a downward component.

2. A form for moulding vertical surfaces of concrete, comprising principal form frame members, flat frame strips supported thereon transversely to said principal members, means adapted to hold said strips thereon edgewise toward the pressure of the concrete, and a covering freely supported thereon to hold the concrete, in which the frame strips are held tilted edgewise slightly away from the horizontal, whereby sagging of the strips under gravity will cause an inward bending of the mould and the pressure of the concrete will consequently be opposed by the weight of the strips.

3. A form for moulding horizontal concrete panels between the beams of a permanent building frame, comprising principal form frame members including cantilevers with a projecting horizontal member adapted to support the form and concrete of said horizontal panel, and a vertical member rigidly connected thereto adapted to support a beam form and the concrete of the beam, and means for supporting said cantilevers from the permanent frame of the building at points near the junctures of said projecting and

vertical members, whereby the weight of the panel is, at least in part, balanced by the weight of the beam.

4. In combination with a form for moulding concrete panels between the beams of a permanent building frame, principal form support members extending beneath the forms from one edge of the panel toward another edge, and saddles for hanging said principal supports from the permanent beams comprising bearing portions adapted substantially to fit the tops of said beams and thereby automatically to assume thereon predetermined positions, and stirrups having thereon means to secure the principal supports thereto and extending from said bearing portions to the mould face a direction and distance adapted to secure a desired relation between the principal supports and the beams when said supports are secured to said stirrups, and whereby the mould can be secured tight against the stirrup and the stirrup will remain in, but will not extend beyond the surface of the concrete after the mould is removed.

5. In a form for moulding a concrete panel upon the beams of a permanent building frame, principal cantilever form frame members extending from opposite sides beneath and each at least half way across the panel, each of which comprises a projecting bearing member adapted to support the form and concrete of the panel, and a vertical member rigidly connected thereto adapted to support the projecting bearing member against its load, said cantilever members being supported vertically near the juncture of the bearing and vertical members and at a substantial distance therebelow supported against the turning moment of its load about said point of vertical support.

6. In a form for moulding concrete, a cantilever member hung from the permanent frame of the building and having a projecting bearing cradle adapted to hold a form beam and to allow relatively large longitudinal adjustment between the bearing member and said beam and a vertical member rigidly secured to said bearing member; a spacer member adapted to hold said vertical member against swinging about its support, a form beam supported in the bearing cradles of said cantilevers at opposite sides of a panel and having spaced slots along its upper edge, flat strips positioned edgewise in said slots in staggered freely overlapping relation, and a covering of stiff, flexible sheet material laid over said strips.

7. In a form for moulding concrete, a combination as defined in claim 6, in which the spacer member connects the vertical member on one side of a beam of the permanent building frame to a similar vertical member on the other side of said beam, and said spacer and said vertical members form principal parts of a beam form frame.

8. In a form for moulding concrete panels between the beams of a permanent building frame, a heavy form beam adapted to carry a major fraction of the weight of a panel form and of the concrete poured thereon to form said panel, and having its upper edge slotted at frequent regular intervals for reception of cross slats, a bearing cradle adapted to engage the end of said form beam inwardly from the edge of said panel a sufficient distance to allow substantial variation in the length of beam which may be used to span the panel area, and having upper edges substantially flush with the top of said beam and slotted

- the same as the beam so as, in effect, to form a continuation of said beam with the slots of both registering in their overlapping portions, slats fitted across said beam and cradle in said slots whereby to form therewith a gridlike frame and to lock the beam and cradle against relative movement, and means for supporting said cradle substantially rigidly in position to hold concrete while it is setting in the panel.
10. 9. A support to be set on a preformed member in a concrete structure, which comprises a hanger adapted to be supported on said member and having a depending stirrup and a bolt threaded through said stirrup and having a shank the shape of which is such as to allow its removal after concrete has been cast around it and set, and which extends against said member to secure said hanger in position on said member while the concrete is being cast.

10. In a form for molding concrete into buildings, a combination comprising principal supports and secondary members supported thereon and a covering of sheet material supported on said secondary members, all held together by gravity, and each separately removable, a temporary support member with a portion thereof extending beneath said secondary supports and adapted to hold them after the principal supports have been removed and another portion over the form covering positioned and adapted to be anchored in the concrete.

11. A combination as defined in claim 10, in which the temporary support is a flexible, easily cut, tie member, and is provided with enough slack to permit removal of the secondary members one at a time without cutting said tie member.

OSCAR M. STANLEY.
